ABSTRACT

Device for locking a shell in, or extracting the shell from, a sleeve of a centrifugal casting machine for casting tubular parts. The device has tong means for extracting the part which are connected to an extracting carriage movable in the axial extension of the sleeve. Locking means for locking the shell in the sleeve are combined with a head having a flange and connected to move axially with the shell. Hooking members pivotably mounted with respect to the carriage cooperate with the flange and are adapted to exert a push or a pull on the head and shell for respectively locking or unlocking the shell. The extracting carriage also carries counter-support abutments for the sleeve.

**DEVICE FOR LOCKING AND EXTRACTING A
CENTRIFUGAL CASTING SHELL AND REMOVING THE
CAST PART FROM THE SHELL**

The present invention relates to the extraction of centrifugally cast tubular parts and more particularly to a device for locking a casting shell to and extracting the casting shell from a shell-carrying sleeve and for removing the cast part. This device is particularly applicable to the casting of liners of internal combustion engines.

It is known that the centrifugal casting of engine liners is carried out in shells or moulds which are mounted inside a rotary shell-carrying sleeve and arranged to rotate with the latter. Owing to their short length, the liners are often cast in pairs in the form of a part capable of affording the two liners in twin shells disposed in end-to-end relation. In this arrangement, if one of the shells has a projection extending across the axial path of removal of the cast part from the shell, the cast part cannot be removed directly. It is first necessary to extract this shell from the rotary sleeve in order to be in a position to remove the cast part from the extracted shell.

An object of the invention is to provide an improved device for locking a shell to a rotary support sleeve so that the shell rotates with the sleeve, unlocking the shell for extracting it, extracting the shell and removing the cast part.

The invention provides a device which is applicable to a shell having a projection precluding removal of the cast part at the end of the shell from which the shell is extracted but allowing the removal of the cast part at the other end of this shell and is of the type having inner extracting tongs for extracting the cast tubular part and an extracting carriage movable in the axial extension of a sleeve carrying the shell, wherein the locking members for locking the shell in the sleeve are combined with a head which is axially integral with the shell and provided with a flange co-operating with push and pull hooks capable of acting on the flange for locking and unlocking the shell, said hooks being pivoted to the extracting carriage which carries counter-support abutments for the sleeve carrying the shell.

According to the invention, the shell is locked very reliably by the pivoted hooks and unlocked in a definite and reliable manner by the same hooks and with the aid of a counter-support on the shell-carrying sleeve. This arrangement results in a smooth production procedure lending itself to an automatic production system on a turntable or moulding line owing to the fact that the shell is always mounted to rotate and extracted correctly.

The invention is particularly applicable to centrifugal casting machines having a rotary sleeve carrying twin shells placed in end-to-end relation for casting a part which extends in the two shells and is such that the part is capable of affording two engine liners.

Further features and advantages of the invention will be apparent from the ensuing description with reference to the accompanying drawings.

In the drawings:

FIG. 1 is a diagrammatic longitudinal sectional view of a device according to the invention in the locking position;

FIG. 2 is a cross-sectional view taken along line 2-2 of FIG. 1;

FIG. 3 is a view similar to FIG. 1 and shows the device in the shell-unlocking and extracting position, and

FIGS. 4 and 5 are diagrams on a scale smaller than that of the FIGS. 1-3, illustrating the stages of extraction and removal of a cast tubular part.

In the illustrated embodiment, the invention is applied to a centrifugal casting machine comprising a sleeve A supporting shells or moulds and mounted on rollers B and driven in rotation at a speed for centrifugal casting, and an extracting carriage C movable in the extension of the axis of the sleeve A.

Mounted in the sleeve A are twin shells or moulds 1^a and 1^b in end-to-end relation and adjoining in a median transverse plane Y-Y. They serve to mould in one operation a part D which is capable for example of affording two engine liners

which are separated, after removal from the shells, by severing along the transverse plane Y-Y. The shell 1^a has, at the end thereof adjacent the extracting carriage C, a flange 2 which extends inwardly and defines one of the end faces of the part D and thus precludes the direct removal of the part D in the direction toward the carriage C.

This extracting carriage C has a cylinder device 3 for shifting an extracting means having jaws 4 which are capable of spreading apart or moving towards each other inside the cast double liner D.

A tubular connecting member or head 5 is fixed axially to the shell 1^a by means of screws 6. This head comprises a trapezoidal outer recess 7 into which radial locking fingers 8 are capable of extending. The fingers 8 extend through the sleeve A and are biased in the direction of the axis X-X by the action of springs, such as 8^a. The head 5 also comprises a flange 9 on which push and pull forces may be exerted in the axial direction by a system which will now be described.

Fixed to the cylinder device 3 are two pairs of twin arms 10. These pairs of arms are symmetrically arranged with respect to the axis X-X. Pivoted near the end of each arm 10 is a U-shaped hook 11 whose ends constitute two fingers 11^a and 11^b which are located on each side of the flange 9 of the head 5.

The hooks are pivoted in pairs on a pin 12 carried by the two arms 10 of a pair of arms. The carriage C also carries a pair of cylinder devices 13 which are arranged symmetrically with respect to the axis X-X and adapted to turn the hooks 11 about their pins 12 through shifting arms 14 (FIGS. 1 and 2).

Mounted at the end of the extracting device 3 through at least one arm 15 is a ring 16 having an axis X-X. Extending axially through the ring 16 are fingers 17 which are adapted to exert a thrust on the flange 9 of the head and are capable of being shifted by end fingers 11^a of the hooks 11.

Each arm 10 terminates beyond the pivotal connection 12 in an abutment 18 which constitutes a counter-support for the sleeve A.

The device operates in the following manner:

To cast the part D corresponding to two liners, the shells or moulds 1^a and 1^b are placed inside the sleeve A and the head 5 integral with the shell 1^a is locked in position by the radial fingers 8 which are urged into recess 7 by the action of their springs 8^a. The latter resist the effect of centrifugal forces

produced by the rotation of the sleeve A. The carriage C, carrying the tongs having the jaws 4, the hooks 11, the thrust fingers 17 and the counter-support abutment 18, is withdrawn, that is, shifted away from the centrifugal casting machine and thus from the sleeve A, to permit the introduction of the molten metal in the shells 1^a, 1^b.

After the metal has been poured, the carriage C is shifted towards the sleeve A for the purpose of unlocking and extracting the shell 1^a and the cast part D, the shell 1^b remaining inside the sleeve A.

After having stopped the rotation of the sleeve A and moved the extracting carriage C towards this sleeve, the cylinder device 3 is supplied with fluid under pressure in such manner as to spread apart the jaws 4 of the extracting tongs (FIG. 3). Thus the cast part D is rendered integral with the shell 1^a and can be extracted at the same time as the shell 1^a.

The cylinder devices 13 are supplied in such manner as to tilt the hooks 11 in such direction that their ends 11^b exert an extracting thrust on the flange 9 of the head 5.

The carriage C of course remains stationary and the counter-support abutments 18 are applied against the ends of the sleeve A.

Thus, the tilting of the hooks 11 exert an unlocking or extracting force on the flange 9 of the head 5. This thrust causes the radial locking fingers 8 to move out of the locking recess 7 while the axial fingers 17 are urged back by the flange 9 of the head 5. This flange is then applied against the ring 16 and rendered rigidly secured to the extracting carriage C. The shell 1^a and the part D are also rendered integral with the carriage C.

The extracting stage now starts (FIGS. 3, 4 and 5). In moving rearwardly, the carriage C disengages the head 5 and the shell 1^a and the part D from the sleeve A (FIG. 3) while the shell 1^b remains in the latter (FIG. 4). This is possible since the shell 1^b has no inner projection preventing movement of the part D. This part D, which is completely disengaged from the shell 1^a, is then seized by a tongs P while the cylinder device 3 is supplied in such manner as to release the jaws 4 (FIG. 4). The carriage C continues to travel rearwardly while the part D is gripped by the fixed tongs P. This results in the complete disengagement of the part D from the shell 1^a. The part D is completely stripped of its shell or mould (FIG. 5). The part D held by the tongs P is discharged by a handling device (not shown).

To cast another part D, the extracting carriage C is moved 15 towards the sleeve A so as to introduce the shell 1^a.

The extracting cylinder device 3 is supplied in such manner that the jaws 4 remain close together (FIG. 1). The cylinder devices 13 first remain supplied in such manner as to cause the ends 11^a of the hooks 11 to apply the flange 9 of the head 5 against the ring 16 and support the head 5 and the shell 1^a and cause them to move in translation with the carriage C. When the abutments 18 about the head 5, the carriage C stops. In this position (FIG. 3), the head 5 is not yet locked. The cylinder devices 13 are then supplied in such manner as to turn the hooks 11 in such direction that their ends 11^a exert a thrust on the fingers 17. This locking thrust is transmitted to the flange 9 of the head 5 (FIG. 1). The recess 7 of the head is then in alignment with the radial locking fingers 8 which first resiliently withdrew, in opposition to the action of their return springs 8^a, to pass over the circular crest defining the inner end of the recess 7 and then move radially forward into the recess 7 under the action of the springs 8^a. At this moment, the shell 1^a is locked in position by the head 5 and the radial fingers 8. The extracting carriage C can then once more withdraw in moving rearwardly so as to make way for the molten metal pouring device.

Owing to the combination of the radial fingers 8 and the recess 7 of the head 5, the shell 1^a is locked in position and the locking and unlocking operations can be carried out since the trapezoidal shape of the recess 7, combined with the rounded shape of the ends of the radial fingers 8, enables the ends of the latter to pass over the annular crest defining the inner end of the recess 7.

Owing to the structure comprising the combination of the flanged head 5, the pivoted hooks 11, the support ring 16 and the counter-support abutments 18 on the sleeve A, the operations for introducing, locking, unlocking and extracting the shell 1^a are carried out in a reliable mechanical manner and

which lends itself to an automatic system.

Owing to the simultaneous extraction of the shell 1^a and part D (FIG. 3), there is no risk of the wall of this part D being deformed (even if it is thin) by the jaws 4 of the extracting 5 tongs since it is supported externally by the shell 1^a.

Note that the thrust fingers 17 transmit an axial thrust force to the head 5.

Having now described my invention what I claim and desire to secure by Letters Patent is:

- 10 1. A device for selectively locking a shell in and extracting the shell from a casting machine centrifugally casting tubular parts and for removing the cast part from said shell, said shell having an internal projection precluding direct extraction of said cast part from said shell, said device comprising inner extracting tong means capable of engaging and extracting the cast tubular part, a sleeve for mounting on said machine and in which said shell is slidably mounted, means defining an extracting carriage movable in an axial extension of said sleeve, a head connected to said shell to move axially with said shell and having a flange, locking means cooperative with said head for locking said shell in said sleeve for casting said part, push and pull hooking means cooperative with said flange for locking and unlocking said shell with respect to said sleeve, said hooking means being pivoted to said extracting carriage, counter-support axial abutment means for said sleeve and mounted on said carriage.
- 20 2. A device as claimed in claim 1, wherein said locking means are radial fingers engageable in an annular recess in said head.
- 30 3. A device as claimed in claim 1, wherein said hooking means are U-shaped members having two end fingers located on each side of said flange, one end finger being operative for pulling said head and the other end finger being operative for pushing said head.
- 35 4. A device as claimed in claim 1, comprising in axial extension of and in spaced relation to said extracting carriage a support ring which is fixed with respect to said carriage and is in coaxial relation to said sleeve and to said head, and thrust members for transmitting the push of said pushing fingers to said flange extending through said ring, said thrust members being parallel to the axis of said ring.
- 40 5. A device as claimed in claim 1, comprising arms fixed in cantilever fashion to said extracting carriage, said arms carrying said counter-support abutment means for axially supporting said sleeve, said hooking means comprising members which are pivoted to said arms and have second arms connected to cylinder devices mounted on the extracting carriage and capable of pivoting said second arms.
